OSCILLATOR

Ernest G. Linder, Surf City, N. J., assignor to
Radio Corporation of America, a corporation
of Delaware

Application August 20, 1935, Serial No. 36,974

12 Claims.

(Cl. 250—36)

My invention relates to oscillators. More specifically, my invention is a multiple magnetron, or a multiple electronic ultrahigh frequency oscillator.

5 One of the objects of my invention is to arrange a number of magnetron oscillators within a common envelope.

Another object is to connect a number of magnetron or electronic oscillators to a single resonant circuit to increase the power developed 10 therein.

A further object is to connect a number of ultra high frequency oscillators across a number of nodal points in a resonant circuit.

15 Other objects will appear in the accompanying specification.

Ultra high frequency oscillations have been generated by magnetron and other types of electronic oscillators. Although it has been feasible 20 to generate extremely high frequencies, it has not been practical to generate large amounts of oscillatory energy. An increase in size of the electronic tube elements increases their interelectrode capacity and decreases their oscillatory frequency. My invention overcomes these 25 difficulties by connecting a number of ultra high frequency oscillators to a single tank or resonant circuit.

In the accompanying figures, Figure I is a 30 schematic diagram of one embodiment of my invention,

Figure II is a detailed perspective illustration of one of the magnetron oscillators and its magnetic circuit, and

35 Figure III is a diagram and a perspective showing of a positive grid oscillator which may be used in my invention.

In Figure I, within evacuated envelope 1 are a plurality of high frequency oscillators 3. Each 40 of these oscillators consists of two anodes 5, 7 and a cathode 9. The cathodes may be filaments or the like and are energized in parallel or series by any suitable source of current which is not shown. A resonant loop circuit 11 connects the 45 anodes 5 and 7. Each of the resonant circuits 11 is coupled to a resonant tank circuit 13, across a nodal voltage point 15. The coupling between 50 3 and 13 is the common portion of the circuits. Instead of coupling directly as shown, the several resonant circuits 3 may be spaced from the single tank circuit 13. In this case the positive connection, represented as 19, must be made directly to each of the several resonant circuits 3 at their mid-points. The coupling may be adjusted by 55 varying the length of the common portion or the

spacing between the two circuits. If the coupling is too loose, the transfer of energy is inefficient. If the coupling is too close, the currents in the separate resonant circuits will react deleteriously on each other. The coupling is determined by 5 the desired width of the transmitted band and the required efficiency.

The tank circuit 13 is resonant to a whole number of half wave lengths. The dotted lines 17 represent the oscillatory voltage along a section 10 of the tank circuit 13, and the polarities indicated are instantaneous values. Each of the resonant circuits 11 is symmetrically arranged about a nodal point in the tank circuit and each of the resonant circuits 11 is properly phased. At a 15 nodal point a connection 19 is made to the parallel wires of the resonant tank circuit 13. An anode battery 21 has its negative terminal connected to the cathode 9 and its positive terminal to the center of the nodal connection 19. An antenna 23 may be connected to the resonant tank circuit 13. 20

If a magnetic field of suitable strength is applied to each magnetron in a position substantially parallel to their cathodes 9, the several magnetrons will generate oscillations. The frequency of each of these oscillations is determined by each of the several resonant circuits 11 and the equation 25

$$\lambda = \frac{k}{H} \quad 30$$

where λ = wave length, k = a constant, and H = the magnetic field strength. Thus it will be seen that each separate oscillator is generating oscillations which may be adjusted to the same frequency. 35 The several separate oscillations may be fed in the proper phase into the tank or resonant circuit 13.

The magnetic fields have been illustrated by circular broken lines labelled magnetic field in 40 Figure I. The fields may be created by a single magnetic circuit having the required number of pole pieces. I prefer to use several separate fields or adjustable pole pieces to facilitate individual adjustment of the magnetrons. In Figure II a 45 magnetic field structure of one type is shown. A magnetic core 31 is energized by a solenoid 33 which is connected through a rheostat 35 to a battery 37. The magnetic field is established between the pole pieces N and S. The field is substantially parallel to the filament 39 of the magnetron. The filament is energized by a battery 41 or any suitable power source. Adjacent the filament or cathode 39 are the anodes 43, 45. The anodes are preferably shaped into a hollow half 50 55

cylindrical form whose central axis is substantially coaxial with the cathode. The anodes are connected by a link circuit 47 which is preferably resonant. A wire or rod 49 represents a section of the resonant tank circuit 13 of Figure I. A fragmentary portion of the evacuated envelope which surrounds the magnetron has been shown to simplify the illustration. The anode battery has been omitted.

10 Although I have illustrated the oscillators as magnetrons, any ultrahigh frequency generator may be employed. In Figure III a positive grid oscillator is shown with the evacuated envelope in fragmentary form. A suitable cathode 51 is energized by a battery 53. Surrounding the cathode is a grid 55. The anodes 57-59 are positioned around the grid and cathode. The anodes are joined by a resonant circuit 61. The resonant circuit is coupled to the tank circuit 63. 15 This circuit is similar to the resonant tank circuit 13 of Figure I. A bridging circuit 65 is connected to nodal points on the tank circuit 63. The center of the nodal connection 65 is joined to a biasing battery 67. This battery biases the 20 anodes either slightly positive or negative with respect to the cathode 51. The grid 55 is connected to the positive terminal of a battery 69 and the negative terminal of this battery is connected to the nodal connection 65. The ultra 25 high frequency positive grid oscillator is well known to those skilled in the art. This oscillator, per se, is not my invention, and a detailed description of the theory of operation is not required. It should be understood that the oscillator of Figure III does not require a magnetic field. 30 The elements of the positive grid or the magnetron oscillator, or both, may be used as the separate generators of oscillations shown in Figure I. I prefer to have separate means for adjusting the 35 several biases of the separate positive grid oscillators.

Various modifications may be made in my invention without departing from the spirit and scope thereof, and I desire, therefore, that only such limitations shall be placed thereon as are necessitated by the prior art and set forth in the appended claims.

I claim:

1. In an oscillatory system, a plurality of magnetron oscillators, a plurality of magnetic fields for said oscillators, a separate resonant circuit connected to each of said magnetrons, a single resonant circuit having a plurality of nodal points, and means coupling each of said separate resonant circuits across separate nodal points on said single resonant circuit.

2. In a device of the character described in claim 1, means for separately adjusting several of said plurality of magnetic fields.

3. In a device of the character described in claim 1, an antenna, and means coupling said antenna to said single resonant circuit.

4. In an oscillatory system, a plurality of positive grid oscillators, a plurality of resonant circuits, means connecting separate circuits of said plurality of resonant circuits to separate oscillators of said plurality of oscillators, a single resonant circuit having a number of nodal points, and means coupling said separate resonant circuits across separate nodal points on said resonant circuit.

5. In a device of the character described in claim 4, a number of sources of voltage for biasing for each of said positive grid oscillators and means for varying said biases.

6. In a device of the character described in claim 4, a single evacuated envelope enclosing said plurality of positive grid oscillators.

7. In an oscillatory system, a plurality of magnetron oscillators, means for creating a magnetic field for said oscillators, a separate resonant circuit connected to each of said magnetrons, a single resonant circuit having a plurality of nodal points, and means coupling each of said separate resonant circuits across single nodal points on said single resonant circuit.

8. In an oscillatory system a plurality of electronic oscillation generators, said generators each including a single electronic oscillator and means for imparting an oscillatory movement to the electrons creating said oscillations; a plurality of circuits each connected to said generators and resonant to said oscillations; a single circuit resonant to a frequency which is a multiple of the resonant frequency of each of said plurality of circuits and further characterized by its adaptability for the establishment therein of standing waves of opposite phases including voltage nodal and antinodal points; means for mutual coupling each of said plurality of circuits to said single circuit in a serial array, whereby each said mutual coupling includes in said single circuit portions of voltage waves of opposite phase and a single voltage nodal point and whereby each said generator impresses oscillations on said single circuit in phasal relations which create said standing waves, and a single evacuated envelope for enclosing said plurality of generators and resonant circuits.

9. In an oscillatory system a plurality of electronic oscillation generators, said generators each including a single electronic oscillator and means for imparting an oscillatory movement to the electrons creating said oscillations; a plurality of circuits each connected to said generators and resonant to said oscillations; a single circuit resonant to a whole number of half wave lengths corresponding to the resonant frequency of each of said plurality of circuits and further characterized by its adaptability for the establishment therein of standing waves of opposite phases including voltage nodal and antinodal points; means for mutual coupling each of said plurality of circuits to said single circuit in a serial array, whereby each said mutual coupling includes in said single circuit portions of voltage waves of opposite phase and a single voltage nodal point and whereby each said generator impresses oscillations on said single circuit in phasal relations which create said standing waves, and a single evacuated envelope for enclosing said plurality of generators and resonant circuits.

10. In an oscillatory system, a plurality of electronic oscillators including a single electronic oscillator and means for imparting oscillatory movements to the electrons in each of said oscillators whereby oscillations of substantially the same oscillatory frequency are created; a plurality of resonant circuits respectively connected to said plurality of oscillators; a single circuit resonant to a multiple of said oscillatory frequency and characterized by having a length adaptable for the creation of standing potential waves of opposite phase and potential nodal points; means for conductively coupling each of said plurality of circuits across different sections of said circuit whereby said coupling includes portions of said potential waves of opposite phase and a single potential nodal point, and whereby said plurality of oscillators create and maintain said

standing waves in said single circuit; and an evacuated envelope including said plurality of generators and said circuits.

11. In an oscillatory system, a plurality of magnetron oscillators, a plurality of magnetic fields for said oscillators, means for imparting oscillatory movements to the electrons in said oscillators, a separate circuit resonant to the period of said oscillatory movements and connected to each of said magnetrons, a single resonant circuit having a plurality of nodal points, and means coupling each of said separate resonant circuits across separate nodal points on said single resonant circuit.
- 5 12. In an oscillatory system, a plurality of magnetron oscillators, a plurality of magnetic fields for said oscillators, means for imparting oscillatory movements to the electrons in said oscillators, a separate circuit resonant to the period 5 of said oscillatory movements and connected to each of said magnetrons, a single circuit resonant to a multiple number of half wave lengths corresponding to said oscillatory movements and having a plurality of nodal points, and means 10 coupling each of said separate resonant circuits across separate nodal points on said single resonant circuit.
